BY *John E. More*
ATTORNEYS.

UNITED STATES PATENT OFFICE

JOHN E. MORE, OF SAN FRANCISCO, CALIFORNIA

DISPLAY CARD

Application filed April 26, 1930. Serial No. 447,522.

This invention relates particularly to a display card apparatus.

An object of the invention is to provide a card display apparatus consisting of a predetermined type of cut-out design, preferably formed out of a single sheet of material and having formed thereon, either by printing, lithographing, or otherwise, a design which will conform to the shape of the 10 cut-out, the design on the cut-out having a portion thereof arranged to form a background continuation of a rack or shelf projected beyond the plane of the front face of the design.

15 A still further object of the invention is to provide a display card consisting of a cut-out sheet of predetermined design, having a rack thereon, for holding articles to be displayed, on the front side thereof, and provided with a rubber suction gripper on the rear side thereof, by means of which said sheet might be positioned or attached to an object for holding the displayed articles in a readily accessible position.

20 Other objects and advantages are to provide a display card apparatus that will be superior in point of simplicity, inexpensiveness of construction, positiveness of operation, and facility and convenience in use and 25 general efficiency.

In this specification and the annexed drawing, the invention is illustrated in the form considered to be the best, but it is to be understood that the invention is not limited to such form, because it may be embodied in other forms; and it is also to be understood that in and by the claim following the description, it is desired to cover 30 the invention in whatsoever form it may be embodied.

In the accompanying one sheet of drawings:

Fig. 1 represents a front elevation of a 35 display card constructed in accordance with my invention and having an article holding rack thereon.

Fig. 2 is a side elevation of Fig. 1.

In detail the construction illustrated in 40 the drawing comprises a sheet of material such as cardboard, laminated wood, or the

like, of relatively thin thickness but yet sufficiently stiff to hold its shape under normal usage. The sheet is cut-out as at 1, to form any predetermined or desired design such, 55 for instance, as that of the woman shown in Fig. 1. It is to be understood that this invention is not limited to the particular arrangement and design shown on Fig. 1 and it would be clearly within the purview of the 60 invention to substitute other shapes and designs in the display card.

The front side of the card would be suitably treated such as by printing, lithographing or engraving, to form thereon the desired 65 design 2, and a portion 3 of said design would be, as shown in Fig. 1, indicated as a background continuation of a rack 4 projecting from the forward side of the sheet. The rack 4 consists of a sheet of material having 70 its opposite ends 5 turned and extended through slots in the sheet, said ends being bent over the back of the sheet and secured thereto either by glue, or clamps, or the like. The rack on the front side of the sheet lies 75 beyond the plane of the said sheet and the coloring or design of said rack is such that when attached to the said sheet, the said rack merges into that portion 3 of the rack, whereby the drawn portion 3 of the rack and the 80 projecting portion of the rack in effect, pictures a rack of relatively large area, whereas the said rack only exists in that portion thereof that projects beyond the face of the sheet.

85 While I have shown and indicated a rack mounted on the forward side of the sheet, it is to be understood that any other type of shelf or shoulder for holding objects to be displayed, might be mounted on the forward side of the sheet, and merged into any design drawn or pictured on the sheet. The type of rack shown is merely illustrative of the idea.

90 The rack 4 along its forward edge is provided with slots 6 therein at spaced points along the length thereof, and objects, such as collar buttons, stick pins, or the like, are adapted to be detachably held in this rack, in such a position that they are readily accessible to be withdrawn for use. Obviously a 95 100

pin cushion, or some other equivalent holding means might be substituted for the rack.

On the rear side of the cut-out sheet at the point where the ends of the rack are attached thereto, I provide a rubber suction gripper 7, which, on one side thereof, is glued or otherwise securely fastened to the rear side of the sheet and to the bentover ends of the

rack. An object in attaching the rubber gripper over the bentover ends of the rack

is to lock the rack ends securely in place and to prevent any dislodgement thereof. The bottom side of the suction gripper 7 is con-

cave and said gripper is formed of pliant rubber, whereby the concavity may be slightly moistened and pressed against a planar

surface and the suction created within the concavity of the gripper will hold the said gripper in place.

Having thus described this invention, what I claim and desire to secure by Letters Patent is:

The combination with a display card made of a sheet cut out to a predetermined design

and having a picture on one side thereof harmonizing with the cut-out design; of a rack for holding articles to be displayed on the

side of the sheet having the picture thereon, said rack being designed to merge into and

form a continuation of a portion of the picture on the sheet; of inturned ends on the

rack extended thru the sheet from the front to the rear side thereof; and a rubber suction

gripper attached on the rear side of the sheet over the extended ends of the rack.

In testimony whereof, I have hereunto set my hand at San Francisco, California, this 3rd day of April 1930.

JOHN E. MORE.
